Filed July 9, 1962, Ser. No. 208,653

2 Claims. (Cl. 328—56)

This invention relates to an electrical circuit for segmentally reversing in time an electrical signal.

In the manipulation of electrical signals containing information it is often useful to reverse the signal in time and then operate on the time reversed signal. This is particularly true with signals having exponential components which die away as time advances where it is necessary to analyze and decompose the signal into orthogonal exponential components. Application for this type of operation is found in the nondestructive testing art in the analysis of signals from the object undergoing test. Present techniques use magnetic tape recordings. However, these methods present difficulties for segments of small duration and become uneconomical when high frequency components exist.

It is therefore one object of the present invention to provide a device for reversing in time an electrical signal.

It is another object of the present invention to provide a device for reversing in time an electrical signal whereby the reversed signal has an expanded or compressed time base with respect to the original signal.

It is still another object of the present invention to provide a device for segmentally reversing in time a periodic electrical signal.

It is yet another object of the present invention to provide a device for segmentally reversing in time a periodic electrical signal whereby reversal or nonreversal of segments thereof may be accomplished as desired.

Other objects of the present invention will become more apparent as the detailed description proceeds.

In general the present invention comprises a first electric transmission line whose sections are connected via switching circuits to associated sections on a like second electric transmission line. A periodic signal is applied to the first transmission line causing a travelling wave to be established thereon. At predetermined time intervals, the switching circuits are energized and permit the travelling wave existing on the first transmission line to be switched to the second transmission line where it causes travelling waves to be propagated therealong in two opposing directions. One of these propagated waves is time reversed with respect to the original signal and hence, when detected at one end of the second transmission line, provides segmental time reversal of the input signal.

Further understanding of the present invention will best be obtained from consideration of the accompanying drawings in which:

FIG. 1 is an illustration of a device for the present invention.

FIG. 2 is an electrical schematic of a preferred embodiment of the device of FIG. 1.

FIG. 3 is graphical representation of the input and output signals of the embodiment of FIG. 2.

FIG. 4 is an electrical schematic of an alternate device for the present invention.

The device of FIG. 1 is shown to illustrate the basic device for the present invention and to facilitate the explanation of the operation therefor. The device comprises a first electrical transmission line 10 having distributed or lumped parameters and a second identical electrical transmission line 12. Switching circuits 14 interconnect associated sections of each of the transmission lines 10 and 12.

In operation, the signal to be reversed 16 is applied to the end of transmission line 10, causing a travelling wave 18 to be established thereon. For the purposes of illustration one cycle of periodic signal 16 is shown on the transmission line 10 with the leading edge thereof approximately at the end of the line 10. At this time, $t=t_1$, switching circuits 14 are actuated which causes the travelling wave 18 on line 10 to be transferred to transmission line 12. This establishes a wave 20 on line 12 which propagates in two opposing directions thereby forming two travelling waves 22 and 24. The wave 22 travelling towards the far end of line 12 is similar to that on line 10 and is dissipated in a line terminating resistor. The wave 24 travelling towards the near end of line 12, is reversed with respect to that on line 10, its leading edge being formed by the trailing portion of wave 18 and its trailing edge being formed by the leading portion of wave 18. The reversed wave 24 appears across a terminating resistor at the near end of line 12 as a signal 26 having a waveform as shown. Thus, by switching travelling wave 18 at time intervals of t_1 it may be continuously segmentally reversed, the signal of a subsequent cycle being fed onto line 10 while the time reversed signal of the prior period is being read at the near end of line 12.

FIGURE 2 illustrates a detailed embodiment for the device of FIG. 1. A first electric transmission line 28 is composed of six L-C sections 30. The inductance of each section 30 is 60 millihenrys and the shunt capacitance 0.002 microfarad. The time delay for each of the section 30 is approximately 11 microseconds and the line 28 has a cutoff frequency of 30 kc. with a characteristic impedance of approximately 5600 ohms. The second electric transmission line 32 is identical to the first line 28. Switching circuits 34 interconnect associated sections 30 of the transmission lines 28 and 32. Each of the switching circuits consists of a 2200 ohm resistor 36 connected in series with a diode 38 across the associated sections of the lines 28 and 32. A phanastron time delay circuit and blocking oscillator (not shown) provide a switching impulse of about one microsecond which is fed via coupling capacitor 39 to the junction of the resistor 36 and diode 38. A biasing circuit (not shown) provides a back bias voltage for each of the diodes 38, thereby permitting significant diode conduction only during the switching impulse.

Operation of the embodiment of FIG. 2 is similar to that previously described for the device of FIG. 1.

The waveform 40 shown in FIG. 3 was applied to the near end of transmission line 28. Waveform 42 was detected across terminating resistor 44 at the near end of transmission line 32. Thus, it can be seen that the output voltage from the embodiment of FIG. 2 is a segmental reversal of the input signal thereto. The time of switching is shown by the small pip 46 near the center of both waveforms 40 and 42.

With the above described embodiment several arrangements are possible by which the waveform of a signal may be controlled and adjusted over a wide range. Expansion and compression of the time base of the reversed signal may be accomplished by varying the design of the second transmission line 32. For example, the output signal time base may be compressed by reducing the time delay of the second line and keeping the number of switching points unchanged. Conversely, expansion may be accomplished by increasing the time delay. Differential expansion in compression of the time base may be accomplished by shortening or lengthening different sections of the second transmission line 32 while maintaining the number of switching points unchanged. Selected portions of the input signal can be eliminated from the output signal by omission of appropriate switching circuits and certain portions of the input signal may be

emphasized or de-emphasized by adjusting the relative gain or attenuation of the various switching circuits. Thus, a wide variety of control over the output waveform 42 may be obtained by using various combinations of these techniques.

In FIG. 4 an alternate embodiment for the practice of the present invention is disclosed. A single electric transmission line 48 having a plurality of L-C sections 50 is used as one arm of a bridge circuit 52. The other three arms of bridge circuit 52 are composed of resistors 54, 56 and 58. A phantastron time delay circuit 57 and blocking oscillator 59 provide a switching impulse through diodes 60 to each of the L-C sections 50 of transmission line 48.

In operation, the input signal is applied across the transmission line 48 and resistor arm 54 of bridge 52. The bridge is balanced; therefore, no output signal appears across the output terminals 62 and 64 of the bridge 52. The applied signal travels down transmission line 48 as in the previously described embodiment of FIG. 2. At the appropriate moment, when the portion of the applied signal to be reversed is all on the transmission line 48, the switching impulse is applied to the diodes 60. The switching impulse causes all the capacitors in the L-C sections 50 to be charged to a potential approximately equal to the peak value of the input pulse. A change in the charge of the capacitors of the L-C sections 50 will occur at this time, dependent upon the difference between the peak value of the switching impulse and the then existing potential on the capacitors due to the initial wave travelling down the transmission line 48. Depending upon this difference a reverse wave will be generated travelling toward the near or input end of transmission line 48. This signal will appear at the output terminals 62 and 64 of bridge 52 and will be segmentally time reversed but will be inverted and will be accompanied by a pedestal resulting from the switching impulse. For example, when the input signal is small or zero a pedestal caused by the switching impulses will be received at the output terminals 62 and 64, since all capacitors in the L-C sections 50 of line 48 will receive near maximum charge.

Persons skilled in the art will, of course, readily adapt the teachings of the present invention to embodiments far different than the embodiments illustrated. Accordingly, the scope of the protection afforded the invention

should not be limited to the particular embodiments thereof shown in the drawings and described above but shall be determined only in accordance with the appended claims.

5 What is claimed is:

1. A device for segmentally reversing in time a periodic signal comprising an electric transmission line having a plurality of capacitor-inductor sections, a balanced electrical bridge having four impedance arms, said transmission line forming one of the impedance arms of said bridge, the input to said bridge being across said transmission line and an adjacent arm of said bridge, the output of said bridge being across said transmission line and the other adjacent arm of said bridge, means for applying said periodic signal to the input of said bridge to generate a periodic traveling wave on said transmission line, and means responsive to said periodic traveling wave for charging the capacitors of said sections of said transmission line whereby a traveling wave is propagated on said transmission line in reverse to said periodic traveling wave, said reverse traveling wave appearing at the output of said bridge and being in time reversal with respect to said applied signal.

2. The device according to claim 1 wherein said periodic signal responsive means comprise a phantastron time delay circuit, a blocking oscillator and a plurality of diodes, said phantastron circuit and blocking oscillator providing a voltage impulse through said diodes to each of the capacitor-inductor sections of said transmission line when said periodic signal is present on said transmission line, whereby the capacitors thereof are caused to charge to a voltage approximately equal to the peak value of said applied voltage impulse.
